UNITED STATES PATENT OFFICE

WALTER J. BAUROTH, OF COLUMBUS, OHIO, ASSIGNOR TO THE JEFFREY MANUFACTURING COMPANY, OF COLUMBUS, OHIO, A CORPORATION OF OHIO

JOURNAL BEARING

Application filed November 19, 1927. Serial No. 234,532.

The present invention relates to certain new and useful improvements in journal bearings adapted to support the armature of an electric motor.

In the practice of coal mining the principal mining operations are conducted at the ever receding working face. The dislodged coal is loaded into cars, and transported from the mine along tracks laid in the mine entries, or galleries. Because of the necessarily restricted dimensions of these galleries the width and height of the locomotive must be kept within extremely narrow limits. The severity of the operating conditions requires unusual strength in all parts of the apparatus. This has caused the development of a type of electric motor the overall length of which is reduced to the least dimensions compatible with efficiency and endurance.

The especial object of this invention is to provide a journal bearing sufficiently rigid to withstand the service conditions encountered in coal mine operations, and of minimum longitudinal dimensions.

Another important object of the invention is to provide means of adjustment for the bearing relative to the shaft to compensate for wear and to maintain the bearing rigid at all times.

The further object is to provide the journal bearing which can be readily dismantled.

Other objects and advantages of the invention will become apparent during the course of the following description.

The means whereby I attain this object are fully set forth in the following specification, and illustrated in the accompanying drawing of which

Fig. 1 is a plan view of an electric motor of the type to which my invention relates.

Fig. 2 is a fragmentary sectional view taken along the line II-II of Fig. 1.

Fig. 3 is a fragmentary enlargement of the driving end of the motor illustrated in Fig. 1.

Like numerals refer to similar parts in the several figures.

In the drawing the numeral 1 refers to the field frame of an electric motor of the totally enclosed type. The numeral 2 refers to the end wall of the field frame 1 in

which is formed an inwardly projecting cylindrical cup 3 adapted to contain the journal bearings in which the armature of the motor is rotatively supported in the manner which will hereinafter be more fully described. Within the frame 1 is mounted an armature including a shaft 4 to which is secured the armature core 5. This shaft is provided with a circumferential shoulder 18, one side of which abuts the core 5 which carries the winding 6 in the manner which is well understood in the art. The proportions of the armature core 5 and winding 6 are such that the longitudinally projecting portions of the winding 6 surround the cup 3 and project into close proximity with the end wall 2 of the motor casing. The armature shaft 4 is mounted concentrically of the cup 3 and projects through a circular aperture in the bottom wall 7 of said cup. Formed in the edge of the bottom wall 7 is an annular groove within which is arranged a suitable packing 8 which contacts with the surface of the shaft shoulder 18 to form a dust and gas tight joint therewith. To the projecting end of the shaft 4 a spur pinion 9 is secured against relative rotation by a key 10 and against longitudinal displacement by the head 11 of a machine screw 12 threaded into a suitable aperture in the end of the shaft 4. The screw 12 is prevented from working loose by a metallic strip 13 fixed to the screw head 11 in any suitable and preferred manner, as by the rivet 14, and on this metallic strip is formed a projection 15 which engages a suitable notch in the face of the pinion 9. Snugly fitting the shaft 4 is the inner race 17 of a ball bearing, the outer race 16 of which snugly fits into the cup 3. This inner race 17 abuts against the shoulder 18 of the armature shaft 4 and is forcibly held in contact therewith by a screw collar 19 screw-threaded to the shaft 4. Formed on the outer face of the collar 19 is an outwardly projecting lug 20 adapted to project between and engage two of the teeth 21 of the pinion 9. By the engagement of the lug 20 with the teeth 21 the screw ring 19 is securely held against rotation relative to the

shaft 4, thus preventing its working loose during the operation of the motor.

The outer periphery of the screw ring 19 is equipped with a L-shaped flange 22 co-operating with a similar flange 23 formed on the inner periphery of an externally threaded ring 24, which takes into threads formed in the outer portion of the cup-shaped depression of the casing 2. The cooperation between the flanges 22 and 23 provides a lap joint between these two screw rings to exclude extraneous matter from the bearing, as well as to prevent the escape of lubricant therefrom. In order to retain the ring 24 fixed in its adjustment relative to the cup 7, a machine screw 25, shown in dotted lines in Fig. 2, is threaded into the wall of the cup with its head fitting in a suitable depression formed in the casing 2, as well as in one of the notches provided in the exterior face of the ring 24.

In assembling the parts above described the ball bearing is slipped into place in the cup 3 with the inner race 17 engaging the shaft 4. The screw ring 24 is then screwed into the cup 7 and locked in place by the set screw 25 in such position as to enable the ring 19 to be threaded home the requisite distance to forcibly retain the bearing in engagement with the shoulder 18 of the shaft. The screw collar 19 is then adjusted to place upon the shaft and tightened up to securely hold the race in working position thereon, after which the pinion 9 is slipped into place upon the shaft 4, the key 10 inserted in its keyway, and the retaining screw 12 tightened up to force the pinion 9 to place, incidentally bringing the lug 20 between two of the teeth 21 of the pinion 9, thereby locking the parts in working relation.

It is to be understood that I do not limit myself to the precise construction here shown since it is evident that the devices here described may be subject to wide variation as to details without departure from the spirit of my invention.

What I claim is:

1. In a journal bearing, the combination with a shaft having a circumferential shoulder, an anti-friction bearing, the inner race of which fits upon said shaft and abuts against said shoulder, a ring screw-threaded to said shaft to hold said inner race in forced contact with said shoulder, a pinion fixed to said shaft outside of said bearing, and a lug on the ring projecting between and engaging the teeth of said pinion as and for the purpose set forth.

2. In a journal bearing, the combination with a shaft having a circumferential shoulder, an anti-friction bearing, the inner race of which fits on said shaft and abuts against said shoulder, a pinion fixed to said shaft outside of said bearing, means to hold said inner race in forced contact with said

shoulder and means on the inner race holding means and cooperating with the teeth of said pinion, as and for the purpose set forth.

3. In a journal bearing, the combination with a shaft having a circumferential shoulder, an anti-friction bearing, the inner race of which fits on said shaft and abuts against said shoulder, a pinion fixed to said shaft outside of said bearing, means screw threaded to said shaft to hold said inner race in forced contact with said shoulder, and means formed on the outer face of said inner race holding means projecting between and engaging the teeth of said pinion as and for the purpose set forth.

4. In an electric motor, the combination with a field frame, a depression formed in the field frame, an anti-friction bearing, the outer race of which fits within said depression, a shaft having a circumferential shoulder, the inner race of aforesaid bearing mounted upon said shaft and abutting against said shoulder, means mounted upon said shaft to hold said inner race in contact with said shoulder, a pinion fixed to said shaft outside of said bearing and means on the inner race holding means cooperating with the teeth of said pinion as and for the purpose set forth.

In testimony whereof I have hereunto set my hand.

WALTER J. BAUROTH.
